UNITED STATES PATENT OFFICE

2,478,011

AUTOMATIC RADIO TUNING MECHANISM

Stanley H. Proffitt, Schenectady, and James A. Choules, Albany, N. Y., assignors to General Electric Company, a corporation of New York

Application January 8, 1948, Serial No. 1,124

10 Claims. (Cl. 74—10.15)

1

This invention relates to automatic tuning mechanisms for radio receivers, and more particularly to an automatic tuner of the sequence type in which a series of predetermined broadcast stations, to which the tuner is adjustably set in advance, are successively and automatically tuned-in by actuation of a single control switch.

It is an object of this invention to provide an improved compact and highly accurate automatic radio tuning mechanism which is relatively simple in construction and which requires low unidirectional operating potential and hence may be conveniently utilized to provide automatic tuning for automobile radio receivers.

A further object of this invention is to provide an automatic tuning mechanism of the turret type, in which the turret remains stationary and a rotatable finger is caused to abut against various adjustable stops carried by the turret, and hence to serve as the position determining mechanism for the radio receiver tuning elements.

Another object of this invention is to provide such a tuning mechanism that may be utilized for selecting a series of predetermined frequency modulation and amplitude modulation broadcasting stations, and in addition to provide manual tuning for both the frequency modulation and amplitude modulation frequency bands.

Still another object of this invention is to provide a single manually-operated device in conjunction with the aforementioned turret which serves as a manual tuning means for the receiver in both the frequency modulation and the amplitude modulation bands, and in addition as an adjusting means for pre-selecting the various broadcasting stations to which it is desired that the tuning mechanism automatically be tuned.

The features of this invention which are believed to be new are set forth with particularity in the appended claims. The invention itself, however, together with further objects and advantages thereof may best be understood by reference to the accompanying drawings, wherein: Fig. 1 shows a panel view of a radio receiver utilizing the proposed automatic tuning mechanism. Fig. 2 shows a view of a radio receiver similar to Fig. 1 with the panel removed. Fig. 3 shows a plan view of the radio receiver. Fig. 4 shows a front view of our improved automatic tuning mechanism. Fig. 5 shows a slightly enlarged view of the automatic tuner similar to Fig. 4, with the front bracket removed. Fig. 6 shows a side view of the tuning mechanism, with

2

several of the components removed to simplify the diagram. Fig. 7 shows a bottom view of the tuner. Figs. 8 and 9 show detail views of various components of the tuning mechanism. Figs. 10a and 10b are diagrams useful in the explanation of the operation of certain components of the tuning mechanism.

Referring now to the drawings, Fig. 1 shows a typical radio receiver utilizing the present invention, and wherein sequential tuning of pre-set stations may be accomplished by remote switching means of well-known type, which may be actuated by the hand or foot of the operator or in any other desired manner. The radio control panel, as may be seen, is extremely simple and comprises three controls. A control designated as 1 has two positions and serves to condition the radio receiver for the reception of either amplitude modulation or frequency modulation stations. A control 2 may serve as the usual volume control, and a control 3 is used to tune the receiver manually through either the frequency modulation or amplitude modulation frequency bands and also to pre-set the mechanism so that the receiver may be tuned automatically to broadcasting stations in either the frequency modulation or amplitude modulation bands by sequence tuning. The usual tuning dial is shown at 4, and provision is made to illuminate either the amplitude modulation broadcast or frequency modulation sections of the dial, dependent upon the particular band to which the receiver is tuned.

Fig. 2 shows a view of the receiver similar to Fig. 1 with the front panel and various associated components removed. In this figure the tuning mechanism is shown generally as 5, various electron discharge devices and other electrical components of the receiver are indicated respectively as 6 and 7. The control 1 is coupled to the tuning mechanism 5 by way of arms 8 and 8' and connecting link 9, the rotation of control 1 causing the tuning mechanism to tune the receiver for the reception of either amplitude modulation or frequency modulation stations, in a manner to be described.

Fig. 3 shows a plan view of the receiver and in this view it can be seen that the control 1 transmits motion to arm 8 and hence to arm 8' through the link 9 by means of a shaft 10 carried by bearings 11. Tuning in the present example is of the permeable type and a plurality of cores 12 are shifted longitudinally in corresponding tuning coils to tune the receiver. The cores 12 are carried on an arm 13, having fixed thereto

a further arm 14 which carries a pulley 15. The arm 14 and pulley 15 moves back and forth in response to the various tuning positions of the cores 12. One end of a cord 16 is attached to the chassis of the receiver at 17, and wound about pulley 15 and about further fixed pulleys 18 and 19. The other end of cord 16 is attached to the free end of a spring 20 which has its other end affixed to the receiver chassis at 21. The cord 16 carries a pointer 22, and it can be seen that this pointer is moved across the dial 4 of Fig. 1 and may be so adjusted that for every position of the cores 12, the pointer 22 indicates the corresponding frequency in the frequency modulation or amplitude modulation band.

A front view of a tuning mechanism is shown in Fig. 4. The cores 12 of Fig. 3 are shown as being six in number and are caused to move longitudinally in the receiver tuning coils which are mounted on coil forms 22'. The coil forms are carried by a panel 23 which may be of fibrous material, and connection may be made to the coils by way of terminals 24 and 25 through this panel. The panel 23 is fixed to the tuning mechanism by means of brackets 26, and is mounted thereon by screws 27. The front bracket 28 of the tuning mechanism is mounted to the receiver chassis by any suitable bracket means, not shown. The bracket 28 carries twelve guide rods 29 which brace together this bracket with a rear bracket in a manner to be described hereinafter. Shaft 30 is carried in the bracket 28 and this shaft is actuated by control 3 of Fig. 1. When rotated, the shaft 30 may be made to tune either the frequency modulation or amplitude modulation bands and when pulled out a short distance and rotated this shaft serves to set up the pre-selected station mechanism in the automatic tuner. An interlocking switch 31 is controlled by the shaft 30 and so arranged that when this shaft is in its forward or extended position, the switch is opened and hence prevents energization of the tuner during the pre-selection set-up procedure. The bracket 28 also carries twelve abutment adjusting screws mounted rotatably on fixed bearings at 32. Two of the above-mentioned adjusting screws are utilized for manual tuning of the respective amplitude modulation and frequency modulation bands, and these screws are resiliently mounted on bracket 28 in such a manner that when the tuning device is actuated thereto, either the switch 33 or switch 34 is caused to close illuminating the suitable section of the dial 4 of Fig. 4.

Referring now to Fig. 7 which shows a bottom view of the tuning mechanism, as previously stated, front bracket 28 is braced to a rear bracket 35 by twelve guide rods 29. Twelve rotatable abutment adjustment screws 36 are carried by the brackets 28 and 35, each of the screws 36 carrying a driving pinion 39, an adjustable abutment 40, a locking nut 41, and compression-torsion spring 42. Rotation of pinion 39 causes abutment 40, nut 41 and spring 42 to move along the screws 36 as a unit, since the guide rods 29 prevent rotation of the above-mentioned abutment nut and spring. The mounting of the above-described adjustment screws is clearly shown in Fig. 6 wherein it can be seen that the screws 36 are mounted rotatably between brackets 28 and 35 in fixed bearings 32, each of these screws carrying a driving pinion 39, an adjustment abutment 40, backing nut 41, spring 42 and a further biasing spring 43.

Referring now to Fig. 8 it can be seen that the shaft 30 is rotatably supported in bracket 28 and

can also be moved a limited longitudinal distance therein. The shaft 30 carries a gear 44 which is driven thereby, and in addition this shaft is coupled to a splined shaft 45 by a coupling 46. The coupling 46 is rigidly carried by the splined shaft 45 and the shaft 30 is rotatably held in this coupling by a key 47. A bracket 48 is fixed on coupling 46, and this bracket carries an idler gear 49.

10 The pinion 39 of any of the abutment screws 36 may be turned by moving shaft 30 forward from the position shown in Fig. 8 to the position shown in Fig. 9, thus carrying gear 44, and idler gear 49 forward and into engagement with one of the pinions 39, the particular abutment screw 36 which is actuated thereby being determined by the angular position of the splined shaft 45. When idler 49 and pinion 39 fail to mesh, spring 50 allows idler 49 to slide on a stud 51, and rotation of shaft 30 causes subsequent meshing of the gears 49 and 39 which in turn shifts the particular abutment 40 along its associated screw 36. Adjustment of the tuning cores is accomplished by resiliently engaging an arm 52 against the respective abutment 40, the arm 52 being integral with a tubular shaft 53, and the shaft 53 being in turn rotatably carried by a sleeve 54. The sleeve 54 is fixed to a sliding bracket 55 and may be integral therewith. The shaft 53 is adapted to rotate spline shaft 45 and slidably engages this shaft. It can be seen that as bracket 55 is caused to slide back and forth, shaft 53 and hence arm 52 is carried therewith. Pressed on the end of shaft 53 is an indexing cam 56, having six teeth 56' and twelve detent depressions 57, as shown in Fig. 7.

15 A manual screw 36' is shown in Fig. 8 and as previously stated two such screws are provided, one for tuning the receiver circuits through the amplitude modulation band and the other for the frequency modulation band. A triple thread may be used on the manual screws in order that the entire tuning range of the respective bands may be covered with a relatively few turns of 20 shaft 30. Screw 36' is spring-urged to the right of the drawing by a spring 55', the tension in this spring being such that when arm 52 engages abutment 40' the screws 36' are moved to the left and stud 32' closes the contacts 33 or 34 25 illuminating a suitable section of the dial 4 of Fig. 1 as previously described. The movement of screw 36' longitudinally to the left of the drawing by the engagement of arm 52 with abutment 40' brings the pinion 39' into the same plane as 30 the idler 49, consequently in this position the idler 49 meshes directly with pinion 39', and hence there is no necessity for longitudinal movement of the shaft 30.

35 Referring now to Fig. 5 which shows an end view similar to Fig. 4 of the tuning mechanism with the bracket 28 removed, this figure shows the pinions 39, abutments 40 and guide rods 29 which are arranged about a circle, concentric to shaft 30. The shaft 30 drives gear 44 which in turn drives respective pinions 39 as selected by the idler gear 49, as previously described.

40 Reference is now made to Fig. 6 which shows the tuning mechanism in the manual tuning position. The arm 52 coacts with abutment 40' causing screw 36' to move to the left of the drawing against spring 55', and stud 32' closes switch 33 illuminating the dial 4 of Fig. 1. As the screw 36' is moved to the left of the drawing, the pinion 39' is brought into the plane of the idler gear 49 and meshes therewith. The rotation of shaft 30

causes screw 26' to rotate and abutment 40' to move longitudinally along this screw. The longitudinal movement of abutment 40' causes the shaft 53 to slide along the splined shaft 45, hence moving the bracket 55 which in turn changes the position of the cores 12 in the tuning coils 58, and hence adjusting the tuning of the receiver.

The sliding bracket 55 is moved back and forth for automatic tuning by means of a solenoid 59, the solenoid 59 being mounted on a bracket 60 by means of screws 61 and the bracket 60 being in turn mounted on the chassis of the receiver. When the coil of solenoid 59 is energized core 62 is drawn into the coil against the tension of spring 63. Movement of core 62 causes the arm 64 which is pivoted to 65 to be driven thereby, by way of link 66. The opposite extremity of arm 64 is coupled to the sliding bracket 55 through a link 67. When the solenoid 59 is energized the sliding bracket 55 is drawn to the right of the drawing, the cores 12 are fully extended and the arm 52 is moved out of engagement with all abutments 40.

Although a solenoid has been shown as the actuated means of the mechanism the invention is not limited thereto, as any driving mechanism such as a motor and cam arrangement may similarly be utilized.

It is contemplated in the present invention to use six adjusting screws 36 for amplitude modulation and six for frequency modulation although the invention is not limited thereto, and it is further contemplated to arrange the amplitude modulation screws alternately with the frequency modulation screws. Therefore, the amplitude modulation abutments are spaced 60° apart. This includes in each instance five preset positions and one manual tuning position.

Amplitude modulation station selection is accomplished by rotating the shaft 53 in steps of 60° thus swinging arm 52 and turning the idler gear 49 about gear 44, this later motion being transmitted by way of splined shaft 45. The above action is accomplished by means of the solenoid 59 acting through arm 64 and link 67 on sliding bracket 55. As shown in Fig. 7 bracket 55 is carried slidably on a guide rod 68 by means of a bracket 69, and on a guide angle 70 by means of roller 74 and further roller placed directly beneath this roller and engaging the opposite side of the guide angle 70. The indexing cam 56 is pressed on the end of shaft 53, which in turn is carried in a sleeve 54 mounted on the bracket 55. As previously described, the indexing cam 56 has six teeth 56' and twelve detent depressions 57. As the cam 56 is carried to the right of the drawing under the influence of solenoid 59, roller 74 moves up an incline 75 on the guide angle 70 and the roller 71 is partially moved out of a detent 57 by arm 72 moving against the tension of spring 73. This occurs as the arm 52 passes beyond the extreme position of any abutment 40. Soon thereafter teeth 56' engage with a bar 76 (Figs. 6 and 7), rotating shaft 53 substantially 50°. When the solenoid is released, bracket 55 moves to the left of the drawing under the influence of spring 63 and as the roller 74 rolls down the incline 75 the roller 71 rotates shaft 53 the remaining 10° as it positively engages a detent 57. The arm 52 now engages a different abutment 40 and a different broadcasting station is thereby tuned in by the mechanism.

The above-described action of the various rollers is clearly shown in Figs. 10a and 10b

5 wherein the bracket 55 engages the guide angle 70 by way of rollers 74 and 79. Fig. 10a shows the roller 74 at the bottom of the incline 75 and rollers 71 engaging a detent 57. Fig. 10b shows the roller 74 at the top of the incline 75 thus moving arm 72 against the spring 73 and releasing the detents from the arresting action of rollers 71.

As shown in Fig. 7, the bar 76 is formed integral with a shaft 77, shaft 77 being rotatably supported by a bracket 78 which in turn is fixed to the supporting bracket of the tuning mechanism. As previously described in connection with Fig. 3, the angular position of shaft 77 is controlled by the arm 8' which is coupled to the control 1 of Fig. 1.

To traverse the 30° between amplitude modulation and frequency modulation settings, bar 76 is rotated 30° by the aforementioned control 1 of Fig. 1. On subsequent energization of the solenoid 59, bar 76 strikes the indexing cam 56 half way down the face of one of the teeth 56' which results in a total rotation, including the action of the detents of 30° in shaft 53, arm 52 and idler 49.

This invention therefore provides a relatively simple, compact tuning arrangement which may be utilized to tune a receiver in the amplitude modulation and frequency modulation bands, 30 and in which this tuning may be accomplished either automatically or manually.

This invention further provides a tuning mechanism in which the settings for predetermined station selection may be changed and adjusted 35 at will, with a minimum of effort.

The present invention further provides an automatic tuning mechanism in which the turret, comprising the various abutments and adjusting screws concentrically arranged about the 40 rotating arm, is stationary and the only moving parts are the shaft carrying the above-mentioned arm and the associated bracket and linkage arrangement. It is obvious that with such an arrangement, the rotating arm may be accurately mounted and an extremely precise mechanism is obtained for positively tuning a receiver to a pre-set station. In addition the complete action of the mechanism is actuated by a single solenoid, motor or other means and a 45 minimum of power is required due to the above-mentioned minimum of moving parts.

While certain specific embodiments have been 50 shown and described it will of course be understood that various modifications may be made 55 without departing from the invention. The appended claims are therefore intended to cover any such modifications as come within the true spirit and scope of the invention.

What we claim as new and desire to secure by 60 Letters Patent of the United States is:

1. Automatic tuning mechanism comprising a movable controlling member, means for imparting reciprocating rotation to said controlling member, an abutment assembly including a plurality of abutments, an arm carried by said controlling member, means for causing said arm to cooperate with said abutments in a predetermined sequence, said last-mentioned means comprising a cam member carried by said controlling member, and a further member, means for causing said cam member to coact with said further member to rotate said controlling member through a predetermined angle when said controlling member is substantially at the extremity of

its reciprocal motion remote from said abutment assembly.

2. Automatic tuning mechanism comprising a movable controlling member, means for imparting reciprocating motion to said controlling member, an abutment assembly including a plurality of abutments, an arm carried by said controlling member, means for causing said arm to cooperate with said abutments in a predetermined sequence, said last mentioned means comprising a cam member, and a further member, means for causing said cam member to coact with said further member to rotate said controlling member through a predetermined angle when said controlling member is substantially at the extremity of its reciprocal motion remote from said abutment assembly, and means for altering the position of said further member to change the sequence of the cooperation of said arm with said abutments.

3. Automatic tuning mechanism comprising a movable controlling member, said controlling member including a rotatable shaft member having an arm and a cam member at the respective extremities thereof, means for imparting reciprocating motion to said controlling member, an abutment assembly including a plurality of abutments, means for causing said arm to cooperate with said abutments in a predetermined sequence, said last-mentioned means including a bar member adapted to engage with said cam member when said control member is substantially at the extremity of its reciprocal motion remote from said abutment assembly, said bar member rotating said shaft member a predetermined angular distance.

4. Automatic tuning mechanism comprising a movable controlling member, said controlling member, said controlling member including a rotatable shaft member having an arm and a cam member at the respective extremities thereof, means for imparting reciprocating motion to said controlling member, an abutment assembly including a plurality of abutments, means for causing said arm to cooperate with said abutments in a predetermined sequence, said last-mentioned means including a bar member adapted to engage with said cam member when said control member is substantially at the extremity of its reciprocal motion remote from said abutment assembly, said bar member rotating said shaft member a predetermined angular distance, and means for altering the angular position of said bar member to change the sequence of the cooperation of said arm with said abutments.

5. Automatic tuning mechanism comprising a movable controlling member, said controlling member including a rotatable shaft member having an arm and a cam member at the respective extremities thereof, means for imparting reciprocating motion to said controlling member, an abutment assembly including a first series of abutments and a second series of abutments alternately spaced with respect to said first series, means for causing said arm to cooperate with the abutments of one of said series in a predetermined sequence, said last-mentioned means including a bar member adapted to engage with said cam member when said control member is substantially at the extremity of its reciprocal motion remote from said abutment assembly, said bar member rotating said shaft member an angular distance corresponding to the angular displacement of the abutments of said series, and means for altering

the angular position of said bar member to change the sequence of cooperation of said arm from the abutments of one of said series to the abutments of the other of said series.

6. Automatic tuning mechanism comprising a movable controlling member, said controlling member including a rotatable shaft member having an arm and a cylindrical shaped toothed cam member at the opposite extremities thereof, means for imparting reciprocating motion to said controlling member, an abutment assembly including a plurality of abutments equidistantly spaced about said shaft member, means for causing said arm to cooperate with said abutments in a predetermined sequence, said last-mentioned means including a bar member coacting with the teeth of said cam member when said control member is substantially at the extremity of its reciprocal motion remote from said abutment assembly, a plurality of detents spaced about the circumference of said cam member, the angular position of said detents corresponding to the angular position of said respective abutments, roller means engaging said detents when said controlling member is substantially at the opposite extremity of its reciprocal motion to the above-mentioned for assuring positive engagement of said arm with said respective abutments.

7. Automatic tuning mechanism comprising a movable controlling member, said controlling member including a rotatable shaft member having an arm and a gear member mounted thereon, means for imparting reciprocating motion to said controlling member, an abutment assembly including a plurality of abutments, each of said abutments being mounted on respective screw members, means for causing said arm to cooperate with said abutments in a predetermined sequence, and means including said gear member for adjusting the position of an abutment with respect to its corresponding screw member when said arm cooperates with said last-mentioned abutment.

8. Automatic tuning mechanism comprising a movable controlling member, said controlling member including a rotatable shaft member having an arm mounted thereon, means for imparting reciprocating motion to said controlling member, an abutment assembly including a plurality of abutments, each of said abutments being mounted on respective screw members, said screw members being movable by individual pinion members, means for causing said arm to cooperate with said abutments in a predetermined sequence, a further shaft member coupled to said rotatable shaft member, gear means sequentially coupling said shaft members to said pinion members when said arm cooperates sequentially with said abutments, and means including said further shaft for rotating said respective screw members to adjust said abutments.

9. Automatic tuning mechanism comprising a movable controlling member, said controlling member including a rotatable shaft member having an arm mounted thereon, electric means for imparting reciprocating motion to said controlling member, an abutment assembly including a plurality of abutments, means for causing said arm to cooperate with said abutments in a predetermined sequence, a further shaft member, means coupling said further shaft member to said rotatable shaft member for adjusting said respective abutments when said arm cooperates therewith, interlock switching means associated with said further shaft member for preventing

energization of said electric means when said further shaft member is conditioned to adjust said respective abutments.

10. Automatic tuning mechanism comprising a movable controlling member, said controlling member including a rotatable shaft member having an arm mounted thereon, means for imparting reciprocating motion to said controlling member, an abutment assembly including a plurality of abutments, said abutment assembly also including manual tuning means, means for causing said arm to cooperate with said abutments in a predetermined sequence, visual indicating means, and switching means associated with said

10 manual tuning means for energizing said visual indicating means when said arm cooperates with said manual tuning means.
